UNITED STATES PATENT OFFICE.

JOHN JAMES ROYLE, OF MANCHESTER, ENGLAND.

ENGINE-LUBRICATOR.

SPECIFICATION forming part of Letters Patent No. 230,066, dated July 13, 1880.

Application filed May 1, 1880. (No model.) Patented in England December 1, 1879.

To all whom it may concern:

Be it known that I, JOHN JAMES ROYLE, of 71 Market street, Manchester, county of Lancaster, England, a citizen of the United Kingdom of Great Britain and Ireland, have invented an Improved Engine-Lubricator, for which I have received Letters Patent in England No. 4,909, dated December 1, 1879; and I do hereby declare that the following is a full, clear, and exact description of the invention.

As applied to lubricating a steam-engine cylinder, I arrange a communication by a suitable pipe from the middle of such cylinder, or thereabout, to the main steam-supply pipe, through a pair of cones or combination of parts similar to those used in an injector, in such manner that as the steam passes the cones a vacuum or partial vacuum is produced, which I utilize for the purpose of inducing the oil to enter the cylinder. Suitable means are provided to feed the oil to the steam-jet in regular and measured quantity.

In the accompanying drawings, Figure 1 represents a side sectional view of my improved engine-lubricator, and Fig. 2 shows the method of connecting the same to a steam-engine cylinder, drawn to a reduced scale.

In both the views A is the body or injector portion of the lubricator, provided with the cones B and C. The inlet-cone B, I prefer to place in direct communication with the main steam-supply pipe D of the engine, and I prefer that the rear of the outlet-cone C should communicate with the engine-cylinder E about the middle in horizontal cylinders and the upper end in the case of vertical cylinders. The suction produced by the steam passing these cones I utilize to draw in the oil or other lubricant, which I cause to fall onto the cup F, as hereinafter described. A valve, G, is arranged to prevent the return of the oil.

It is an oil cup or receiver mounted upon the bracket I, projecting from the injector-body A, and provided with a loose cover, J.

K is a regulator for controlling the quantity of oil to the cup F, and consequently the quantity fed to the engine. This regulator K consists of a screwed cap, which can be made to more or less cover a small hole, a, in the tube L, and so regulate the quantity of oil dropping on the cup F to the greatest nicety.

From the foregoing description it will be apparent that at each successive period of low pressure in the cylinder a jet of steam passes through the cones B and C, and the suction produced thereby opens the valve G and draws in any oil that may have been fed to the cup F and carries it into the cylinder E. At the period of high pressure in the cylinder the valve G closes, and so prevents the oil returning.

In Fig. 3 I illustrate the same lubricator arranged for locomotive and other engines which work intermittently, and in which the feed of oil is not visible, as in Fig. 1. In this case the oil-cup H is mounted directly over the body A, and the check-valve G has a long spindle, G', passing up through the tube M, and which valve is held up to its seat by a spring, O. A sleeve, P, fits round the tube M, and its lower part is formed as a plug-tap, with a small hole, R, corresponding to a similar hole in the fixed tube M.

By turning the sleeve P, by means of the milled head S, the amount of passage through the hole R may be varied, and consequently the oil passing to the valve G regulated to the greatest nicety. The relative position of the holes is shown by a pointer, T, sweeping over an index, U.

V is a lock-nut for fixing the sleeve P in position.

It will be seen that the lower portion of the tube M, Fig. 3, performs the functions of the cup F, Fig. 1, and the main part of said tube M, from the bottom of the cup H upward, performs the functions of the tube L, while the sleeve P performs those of the cap K. The upper neck of the injector-body A receives the enlarged and threaded lower end of the tube M in place of the cup F, and a plain screw-cap, X, of a like pattern at its inner end, takes the place of the screw-cap to which the bracket I is attached. The injector-body A is the same in both cases, and its interior is clearly shown in Fig. 1.

In each form of my lubricator a regulated escape of the lubricant from the cup H, say one drop per stroke, passing by gravity to the oil-inlet of the injector A, is carried into the cylinder E by injector-action at each succeeding period of low pressure without reliance

upon the slow flow of the lubricant and without the manipulation of any cock or valve by the engineer, the entire operation being automatic.

5 I am aware that an engine-lubricator has been constructed with a steam-connection, so as to provide for blowing the oil from a hollow cock when the latter is opened.

My lubricant-injector, with suction-cones, 10 does not depend on any opening or closing of cocks, but, as applied to a steam-engine, operates automatically while the steam is on, as aforesaid, under the control of the pressure in the cylinder, and the injector action is superior 15 in that it carries the lubricant into the cylinder in the form of spray, and thus facilitates its access to every part of the circumference of the cylinder.

I am also aware that check-valves similar to 20 my valves G, and also an escape-regulator consisting of one perforated tube within another, have been used in other lubricators.

In my combinations the valve G is opened and closed by the injector-jet under control of 25 the pressure in the cylinder, and the escape-regulator K L or P M simply controls the passage of the lubricant to the inlet of the injector A, from whence it is carried into the cylinder by injector-action, as aforesaid.

30 Although I have found the method of fixing the lubricator herein described to give the best results in practice, I would observe that it is not essential that the steam-supply be taken from the main steam-pipe, as it may be taken from the valve-box of the engine or from either 35 end of the cylinder.

It will be obvious that this arrangement of 40 lubricator is also applicable for lubricating

gas, air, and other engines operating in a similar manner, and that it is suitable for feeding 45 oil, tallow, grease, or other lubricant.

Having now fully described my invention, together with the best methods with which I am acquainted for carrying the same into practical effect, I wish it to be understood that 45 what I claim, and desire to secure by Letters Patent, is—

1. The combination, in an engine-lubricator, of a cup for supplying the lubricant, means for regulating the escape from said cup, and 50 an injector having suction-cones, an inlet for the lubricant, an inlet for the steam or its equivalent, and a connection with the engine-cylinder, arranged and operating substantially as herein described, the lubricant being carried into the cylinder by injector-action, as set forth.

2. The combination, in an engine-lubricator, of a cup for supplying the lubricant, means for regulating the escape from said cup, and 60 a check-valve with an injector having suction-cones, an inlet for the lubricant, an inlet for the steam or its equivalent, and a connection with the engine-cylinder, substantially as herein specified.

3. The regulating-sleeve P R, Fig. 3, in combination with the supply-cup II, having the inclosed escape-tube M, the check-valve G, seated at the lower end of said escape-tube, and the injector A, substantially as herein 70 specified, for the purposes set forth.

JOHN JAMES ROYLE.
